RACKET OR THE LIKE

Milton B. Reach, Springfield, Mass.

Application June 20, 1939, Serial No. 280,159

13 Claims. (Cl. 273—73)

The object of this invention is to provide a distinctive type of racket for tennis, badminton, squash, or the like, or the like implement that lends itself to the economies of mass production in operations of manufacture with uniformity of product that does not exist under present orthodox methods of assembly.

The weak part of a racket is that area where the bow merges and joins the handle or throat portion, and one of the principal objectives of this invention is to give the strength of metal to that area without detracting from the playing qualities of the racket, and to provide a union of metal and wood in this area of a permanent form free from any play or chatter.

Very narrow limitations of weight are imposed in this type of athletic implement, and the combination of metal and wood incorporating requisite strength and lightness is one of the objects accomplished by the applicant's type of assembly.

The following is a description of the means by which the desired results are accomplished.

In the drawings

Figure 1 shows a bow of a racket made according to and embodying features of my invention.

Figs. 2 and 2c are views of a yoke member forming connecting means between the bow and the handle of the racket. Figs. 2a, 2b, and 2d are sectional views of details of the yoke member of Figs. 2 and 2c, on lines A—A, B—B, and D—D, respectively, and slightly enlarged.

Fig. 3 shows a ferrule or thimble also preferably forming a part of the connection. Fig. 3c is a section on line C—C of Fig. 3, slightly enlarged.

Fig. 4 is a view of the handle or grip of the racket. Fig. 4d is a slightly enlarged section on line D—D of Fig. 4.

Fig. 5 is a view of the assembled racket frame, with stringing partly shown.

Fig. 6 shows an alternative construction employing rivets. Fig. 6a is a detail of the rivet.

Fig. 7 is a view of a unitary bow or head member in the form of a closed curve and made of two pieces or strips of material.

In the ordinary type of racket, the "bow" of the frame is manufactured with a stem extension that forms the handle portion, or, in some instances, a part of the handle portion which is supplemented with an additional gripping section of desired size and shape.

I propose to separate this manufacture into two distinct units. A "bow" section 1, which I plan to make preferably of one long strip of thin fibrous material, like wood, wound around upon

itself into a desired oval or circular form, the different convolutions being cemented or glued one upon the other to produce a unitary whole, as seen in Figure 1, of laminated form.

The method of doing this forms the subject matter of a separate application, but it will be readily understood that these "bows" fashioned in an endless form permit facility of manufacture in the various shaping, drilling and sanding operations, as multiple units may be ganged together and worked upon as a group with perfectly uniform results. Also in the subsequent varnishing, finishing and stringing operations these stemless bows lend themselves to greatest ease of handling.

It is not desired to limit the invention to a bow comprising a single strip of material wound upon itself in the exact form shown with ends of the strip at the same end of the bow, as it will be apparent that the ends of the strip may be disposed at opposite ends of the bow, or otherwise about the bow, or may be made of more than one strip of material, the invention concerning a stemless bow in the form of a closed curve which desirably may be made of fibrous material, such as wood, wound upon itself in laminated form, although it may be made of other material. A bow made of two strips of material is shown in Fig. 7, and desirably comprises two pieces of bent wood, one within the other, and tapered down at opposite ends of the bow to preserve uniform width, the outside bow member or piece being of full width at the top and tapering down to nothing where it is to be received within a metal yoke member which will protect the thinned parts.

Following the manufacture of the bow portion, there is assembled thereto a yoke element 2 (Fig. 2) preferably formed from a thin strong metal alloy in a shape to fit the bow portion. Preferably I line the inside channel of this thin pressed metal yoke with a lining member 3 desirably of rubberized fabric which is vulcanized to the metal by established practices, such as by using a material, such as that known as thermoprene.

Thermoprene may be described as a product of the general type of that produced by the reaction of rubber with an agent selected from the group consisting of sulfuric acid, sulfonic acids, and sulfonyl chlorides. It is not desired, however, to restrict the invention to the use of this particular bonding material.

I then roughen the surface of this lining member or fabric by a sanding operation and coat it with a suitable adhesive to produce a good strong

union with the bow portion under pressure, the bow portion desirably being of wood or other non-metallic material. An alternate method of riveting or bolting, as indicated in Fig. 6, may be assumed, but I prefer the chatter-free solidity and unity of a glued or cemented joint between the rubberized cloth or fabric lining and the bow portion, although there is presented in a bolted or riveted connection an opportunity to repair a racket having broken strings by substituting a complete new bow portion at a relatively slight increase in cost.

The metal yoke 2 preferably has extruded from its bottom surface, a short shoulder-like section 15 4 of a suitable shape, desirably substantially a flat oval shape, over which may be brazed, or otherwise applied, a formed flanged thimble 5 (Fig. 3), which acts as a support for the hollow metal handle section 6, which may be pushed over 20 the reduced end 5a of the thimble. Desirably I may use thermoprene or the like, and apply rubberized fabric 7 to the outside of the shoulder 5a of the thimble, and the handle portion 6 may be driven over this and held by friction.

25 The handle portion 6 I prefer to make from a seamless alloy tubing material with suitably thin walls, drawing the upper end to whatever cross-section shape may prove of current style (at present the taste runs to an extreme streamline 30 appearance) and forming the lower or grip end 6a into the flat sided forms prevailing in the various types of rackets of this period. I then propose to cover the grip section of the handle with leather having multiple perforations to provide an 35 aerated grip section to insure a comfortable, dry grip.

It may be noted that in shaping the stem of the handle sections, its cross-section diameters may be designed to move the "whip" of the racket 40 toward the bow or reverse, and that "balance" may also be controlled to some extent in this design.

In all types of rackets, the essentials of manufacture, comprising an endless and stemless and 45 unitary bow portion in combination with a handle portion and a metal yoke connecting the two, prevail, and it is in these broad essentials that I claim new improvements in the art of this manufacture.

50 Where riveting or bolting 9 is used to secure the yoke to the bow or head, as indicated in Fig. 6, a compressible lining member 10 such as of rubber or fabric or the like may preferably be employed between the yoke and the bow to prevent 55 chatter under impact. The rivets 9 may desirably be of a standard light tubular form, such as comprising two telescoping cylinders, with the inner and longer one passing through the other, and with its end upset until both parts are drawn 60 tightly against their respective shoulders.

It is conceivable that by the present invention 65 assembly of the racket can be made so cheaply that the head or bow may be readily replaced, as when string breakage occurs, by inserting a new bow or head already strung at the factory, instead of having restrung operations performed at stations all over the country. The invention thus contemplates also a unitary endless stemless bow which may be strung prior to assembly with 70 the yoke and handle of the racket.

75 Preferably, however, the racket is strung after the bow is assembled with the metal yoke, in which case the yoke is provided with perforations 11 to receive the string.

It is not desired to restrict the invention to the

yoke member 2, thimble 5, and handle 6 being made separate, as it will be apparent that these parts could be made in one piece, or in two pieces, instead of three, if desired, without departing from the invention.

5 The channel shaped yoke member 2 preferably has a corrugation or reentrant portion in its bottom providing a raised portion or groove 8, which provides a recess for the string to lie in where the stringing is done after assembly of the bow 10 and yoke, and the corrugation 8 also reduces the strain of impact against the side of the yoke, at the same time increasing the area of the gluing surface.

The bow is grooved as indicated at 12 to conform to the raised bead or corrugation.

I claim:

1. A racket or the like comprising a bow or head of wood or the like consisting of a closed curve, a member of metal or the like secured to 20 a circumferential part of the closed curved bow or head at the handle side of said bow or head, and providing the strength of metal at the area of union with the closed curved wooden bow with requisite lightness, and handle means connected 25 with said metal member, said metal member being of channel form receiving a portion of said closed curved bow or head, said metal channel member being secured to said closed curved wood bow portion by a lining member interposed between them and secured to both.

2. A racket or the like comprising a bow or head of wood or the like consisting of a closed curve, a member of metal or the like secured to a circumferential part of the closed curved bow or 35 head at the handle side of said bow or head, and providing the strength of metal at the area of union with the closed curved wooden bow with requisite lightness, and handle means connected with said metal member, said metal member being of curved channel form receiving a portion of said closed curved bow or head and embracing the same, a lining member in said metal channel member disposed between it and the said wood bow or head portion and secured to both, said 45 connecting lining being adhesively secured to the curved wood bow and vulcanized to the metal channel member.

3. A racket or the like comprising a complete unitary bow or head consisting of a closed curve 50 of material in strip form providing laminations and reduced lapped portions, a thin pressed metal member secured to a circumferential part of the laminated closed curved bow or head at the handle side of said bow or head, said metal member providing metallic strength at the area of union with the closed curved laminated bow with requisite lightness, and handle means connected with said member, said metal member having a stem portion, a metal thimble secured to said 60 stem portion as by brazing or the like, and a tubular metal handle secured to said thimble, said thimble having rubberized fabric vulcanized thereto, and said tubular metal handle being driven thereover in a friction connection.

4. A racket or the like comprising a bow or head in the form of a closed curve, a thin pressed metal member secured to a circumferential part of the closed curved bow or head at the handle side of said bow or head, said metal member having a curved portion of channel shape conforming to and receiving said closed curved bow or head, and providing the strength of metal at the area of union with the closed curved bow with requisite lightness, and handle means connected with said 75

member, said metal channel member having a corrugation or raised bead formed in its bottom said bow being grooved to correspond.

5. A racket or the like, according to claim 1 in which said metal channel member is additionally secured to said wood bow by rivets or the like, extending through the side walls of the channel and bow, said lining member being of rubberized fabric and preventing chatter.

10. 6. As an article of manufacture, a complete bow or head for a racket or the like consisting of a closed hoop composed of a plurality of laminations of material in strip form wound one upon another, said laminations being continuously curved 15 in the same direction, said complete laminated closed bow or hoop including reduced strip ends, said reduced strip ends being lapped upon an adjacent portion of said strip material and providing a lapped reduced strip end constituting 20 a part of the inner peripheral surface of said complete laminated closed bow hoop and another lapped reduced strip end portion constituting a part of the outer peripheral surface of said complete bow.

25. 7. An article of manufacture according to claim 6 in which said complete closed curved bow or head for a racket or the like, comprises inner and outer strips of material, the widest central portion of the length of the outer strip being disposed adjacent the top side of the bow and having tapered reduced end portions disposed adjacent the handle side of the bow, the inner strip being in a reverse relation with the widest central portion of its length adjacent the handle side of 30 the bow and its tapered reduced ends adjacent the top portion of the bow, and disposed within 35 the outer strip.

8. An article of manufacture according to claim 6 in which said complete bow hoop comprises laminations of wood or like fibrous material 40 in strip form.

45. 9. A racket or the like comprising a complete unitary bow or head consisting of a closed hoop composed of a plurality of laminations of wood or like non-metallic fibrous material in strip form wound one upon another, said laminations

being continuously curved in the same direction, said complete laminated closed bow or hoop including reduced strip ends, said reduced strip ends being lapped upon an adjacent portion of said strip material and providing a lapped reduced strip end constituting a part of the inner peripheral surface of said complete laminated closed bow hoop and another lapped reduced end portion constituting a part of the outer peripheral surface of said complete bow, a thin metal member secured to a circumferential part of the complete laminated closed hoop or bow at the handle side of said bow and providing metallic strength and requisite lightness at the area of union with the laminated closed hoop, and handle means connected with said thin metal member.

10. A racket according to claim 9 in which a reduced lapped strip end portion of said unitary laminated closed hoop or bow is disposed on the outside of the bow at the handle side of said bow 20 and is engaged and protected by the thin metal member.

11. A racket or the like according to claim 9 in which said thin metal member comprises a yoke having a channel shaped portion curved to receive and conform to a peripheral portion of said unitary laminated non-metallic closed hoop or bow and a stem portion extending substantially centrally from said channel shaped portion, and handle means connected with the stem portion of 30 said yoke.

12. A racket or the like according to claim 9 in which said thin metal member comprises a yoke having a channel shaped portion curved to receive and conform to a peripheral portion of said unitary laminated non-metallic closed hoop or bow and a stem portion extending substantially centrally from said channel shaped portion, a tubular metal handle, and a metal thimble or ferrule secured to and connecting said stem portion 40 and said tubular metal handle.

13. A racket or the like according to claim 9 in which said complete bow hoop comprises laminations of wood or like fibrous material in strip form.

45. MILTON B. REACH.
